UNITED STATES PATENT OFFICE.

BURTON B. BENNETT, OF DETROIT, MICHIGAN, ASSIGNOR, BY MESNE ASSIGNMENTS, TO DAISY MANUFACTURING CO., OF PLYMOUTH, MICHIGAN, A CORPORATION OF MICHIGAN.

AIR-GUN.

No. 897,813.

Specification of Letters Patent. Patented Sept. 1, 1908.

Application filed April 12, 1907. Serial No. 367,838.

To all whom it may concern:

Be it known that I, BURTON B. BENNETT, a citizen of the United States of America, residing at Detroit, in the county of Wayne 5 and State of Michigan, have invented certain new and useful Improvements in Air-Guns, of which the following is a specification, reference being had therein to the accompanying drawings.

- 10 The invention relates to an air gun provided with the usual plunger and actuating spring therefor, and consists in the construction of a firearm of this type wherein the compression of the spring and the shifting of 15 the plunger are effected at different periods, instead of simultaneously as heretofore, resulting in a material decrease in the power required to cock the gun, and providing a firearm that can be easily operated.
- 20 The invention further consists in the peculiar arrangement and combination of the gun parts, and further in certain details of construction as will be hereinafter set forth.

In the drawings,—Figure 1 is a vertical 25 central section through an air gun embodying my invention, partly in elevation, the parts being shown in the position for shooting; Fig. 2 is a similar view, showing the gun in the process of cocking; Fig. 3 is an enlarged longitudinal section through a portion 30 of the gun, illustrating the construction and arrangement of the barrel; Fig. 4 is a cross section through the barrel, showing the same in the loading position; and Fig. 5 is a detached perspective view of the reciprocating 35 member for compressing the spring, and its connections with the stock.

The reference-letter A indicates the stock 40 of the gun, terminating at its forward end in a hollow frame B, slotted in its lower portion, as at C.

D is a casing pivoted to the frame B of the stock at E, the connection being such as to provide a "breakdown" construction similar 45 to a breech-loading gun, and F represents the gun barrel secured to the casing in a manner to be hereinafter described. Within the casing D is an air compression cylinder G, in which a plunger H of any suitable type 50 works.

H' is a plunger rod, terminating at its free

end in a hook H², and I is the actuating spring for the plunger, preferably of the coil type and encircling the rod as indicated.

J represents the usual projectile-starting 55 rod made hollow and provided with an inlet K for the admission of the air, the free end of the rod projecting through an opening L in the forward end of the compression cylinder.

M represents a plug section made integral 60 with the compression cylinder, and adapted to completely fill the forward end of the casing D, and O is an opening extending longitudinally through the plug section for a purpose to be hereinafter described. The 65 means employed for compressing the spring and shifting the plunger is a reciprocating member P, the member being made hollow, and the parallel walls P' and P² being in proximity to one another so as to form a guide- 70 way to receive the rod H'.

Q designates the usual trigger held in its retaining position by a spring R, the trigger being pivoted to the reciprocating member and carried with it during its travel to and 75 fro in the casing.

As the means for reciprocating the member P, a link S is preferably employed extending through a slot T in the reciprocating member, and having a pivotal connection 80 with the latter, and being preferably connected at its opposite end to the frame B of the stock, the end portion U of the lever extending within the opening C of the frame, as plainly indicated.

In the operation of cocking the gun, the stock is broken down, as indicated in Fig. 2, causing the reciprocating member encircling the plunger rod to bear against and compress the spring, the operation of compressing being continued until the hook upon the plunger rod engages the trigger. Upon closing the breech of the gun, the reciprocating member is retracted, drawing with it the plunger, thus shifting the latter into its shooting position. The missile is then inserted within the gun barrel, as hereinafter set forth, and the gun is in readiness for use.

It will be obvious from the construction 100 described that any form of operating means may be employed for reciprocating the member P, and I do not desire to be limited

to the particular actuating mechanism shown, although I deem the same preferable in use, as the reciprocation of the member can be more readily effected by the increased leverage that the gun stock in the breaking-down operation produces.

The barrel F referred to is connected to the casing D in alinement with the air compression chamber, and is shiftable longitudinally of the casing, and the connections are of such a character that the barrel may be rocked or shifted out of alinement with the casing into a loading position to receive the projectile. The rear end of the barrel V is 15 slightly reduced, and adapted to extend a short distance within the forward end of the casing, while a pivot-pin W secured to the barrel extends within the opening O in the plug section of the casing, and a short distance therebeyond, terminating in a head X. A spiral spring Y is interposed between the head and the plug section, and serves to hold the barrel normally in alinement with the compression chamber.

20 To load the gun, the barrel is adjusted axially of the casing a sufficient distance to clear the casing end, and then rocked or rotated sidewise into the position shown in Fig. 4 to permit of the insertion of the projectile.

In addition to the pivot-pin W described serving as the main connection between the barrel and the casing, I preferably proportion the parts so that the projectile-starting rod J 35 will extend, when the plunger is in the firing position, slightly within the barrel flush with the casing end, as plainly shown in Fig. 1, the projecting portion of the rod J constituting additional securing means for holding the 40 barrel in its operative position.

From the foregoing description it will be readily seen that the work required in cocking the gun is divided, a part being performed during the breaking-down of the 45 stock, and the balance in restoring the gun to the shooting position, and thus the power necessarily employed in the operation of cocking is reduced to a minimum.

While I have shown the preferred mechanism for accomplishing this result, I do not wish to be limited thereto, as my invention 50 contemplates broadly the shifting of the plunger and the compression of the plunger spring at different intervals during the operation of cocking instead of simultaneously as heretofore with the attendant disadvantages.

What I claim as my invention is,—

1. In an air gun, the combination with a 55 stock, of a casing connected thereto provided with an air compression chamber, a spring-actuated plunger working within said chamber, and means associated with said plunger for first compressing the plunger spring and

subsequently shifting the plunger during the 65 operation of cocking.

2. In an air gun, the combination with an air compression chamber, of a spring-actuated plunger working therein, a reciprocating member, means associated with said member and plunger compelling during the operation 70 of cocking, first the compression of the plunger spring upon movement of the member in one direction, and subsequently the shifting of the plunger upon its travel in the opposite direction, and means for reciprocating the 75 member.

3. In an air gun, the combination with an air compression chamber, of a plunger working therein, an actuating spring for the plunger, a reciprocating member, means associated 80 with said member, and the plunger acting to compress and retain the plunger spring upon movement of the member in one direction, and to shift the plunger and spring upon its travel in the opposite direction, and means 85 for reciprocating the member.

4. In an air gun, the combination with a stock, of a casing pivoted thereto and provided with an air-compression chamber, a spring-actuated plunger working within said 90 chamber, a reciprocating member in operative relation to the plunger adapted upon reciprocation to successively compress the plunger spring and shift the plunger, and an operative connection between said reciprocating member and the stock.

5. In an air gun, the combination with an air compression chamber, of a spring-actuated plunger working therein, the plunger stem or rod, a reciprocating member in operative relation to the plunger spring, a trigger carried 100 by said member adapted to engage the rod, and means for reciprocating said member.

6. In an air gun, the combination with an air compression chamber, of a spring-actuated 105 plunger working therein, the plunger stem or rod, a reciprocating member in operative relation to the plunger spring, a trigger carried by said member adapted to engage the rod, and a link for reciprocating said member.

7. In an air gun, the combination with a stock, of a casing pivoted thereto, an air compression cylinder within the casing, of a spring-actuated plunger working therein, a plunger rod, a reciprocating member in operative 115 relation to the plunger spring, a trigger carried by said member adapted to engage the rod, and a link connection between the reciprocating member and stock.

8. In an air gun, the combination with a 120 casing provided with an air compression chamber therein, of a spring-actuated plunger working within the chamber, a reciprocating member within the casing formed with a guide-way, a stem or rod for the plunger 125 carrying a hook extending within the guide-

way, a trigger pivoted to the reciprocating member in operative relation to the hook, and means for reciprocating the member.

9. The combination with a casing provided with an air compression chamber, of a barrel lining with said chamber and connected to the casing for relative rocking movement, a spring-pressed plunger working within the compression chamber, and a projectile-start-

ing rod extending in its firing position partially within the barrel and acting to hold the latter against relative rocking movement. 10

In testimony whereof I affix my signature in presence of two witnesses.
